UNITED STATES PATENT OFFICE.

LEONARD A. YOUNG, OF DETROIT, MICHIGAN.

DESIGN FOR A GOLF BALL.

Application filed October 20, 1927. Serial No. 23,828. Term of patent 14 years.

To all whom it may concern:

Be it known that I, LEONARD A. YOUNG, a citizen of the United States, residing at Detroit, county of Wayne, State of Michigan, have invented a new, original, and ornamental Design for Golf Balls, of which the following is a specification, reference being had to the accompanying drawing, forming a part thereof, in which the figure is a

plan view of a golf ball embodying my new design, it being understood that the entire surface of the ball is covered with the design as indicated, the stars being sunk within the surface of the ball.

I claim:

The ornamental design for a golf ball, as shown and described.

LEONARD A. YOUNG.
